SWITCH KNOB

Melvin Boldt, Chicago, Ill., assignor to Moffats Limited,
Weston, Ontario, Canada, a company of Canada

Filed May 9, 1961, Ser. No. 65,083

Claims priority, application Canada Apr. 27, 1961

Term of patent 14 years

(Cl. D26—13)

FIG. I

FIG. 2

FIG. 3

FIG. 1 is a perspective view showing a switch knob embodying my design;

FIGURE 2 is a side elevational view of the switch knob of FIGURE 1, and

FIGURE 3 is a sectional view taken along line 3-3 of FIGURE 2.

I claim:

The ornamental design for a switch knob, as shown.
